UNITED STATES PATENT OFFICE.

CHARLES W. HORNUNG, OF JERSEY CITY, NEW JERSEY, ASSIGNOR TO HIMSELF, AND SHERWOOD R. KNAPP AND HERBERT J. KNAPP, OF BROOKLYN, NEW YORK.

METHOD OF MOVING TRAINS.

SPECIFICATION forming part of Letters Patent No. 701,045, dated May 27, 1902.

Application filed February 4, 1902. Serial No. 92,569. (No model.)

To all whom it may concern:

Be it known that I, CHARLES W. HORNUNG, a citizen of the United States, residing at Jersey City, in the county of Hudson and State 5 of New Jersey, have invented new and useful Improvements in Methods of Moving Trains, of which the following is a specification.

By means of this invention railroad-trains can be moved through tunnels or yards or 10 other localities practically without smoke or steam; and the invention resides in the features set forth in the following specification and claims and illustrated in the annexed drawings, in which—

15 Figure 1 is a side elevation of a track or way provided with this invention. Fig. 2 is a plan view of Fig. 1. Fig. 3 is a section along $x x$, Fig. 1.

This train-moving system is shown as comprising tracks or track-sections a , b , and c . The section or part a is the main track, on which a train is moved or run in the ordinary way—say by locomotive. In passing some localities it may be necessary or desirable to 20 avoid the creation or emission of smoke and steam—as, for example, in a tunnel, where signals might thus become obscured or hidden. At such a locality a section of track, as b , provided with one or more train-carrying trucks d , driven by smokeless medium, as electricity or compressed air, will enable the train to be carried along or, as it might be called, “ferried,” while the locomotive is inactive—that is, emitting practically no 25 smoke or fumes. The section b is on a different level from main track a , so that the trolley or carrying-truck d will have its top or train-receiving part level with such main track a for a train to be run off the main track 30 onto the truck or float b and also from the truck b onto the main track. When on the truck, the locomotive can shut off steam, and the truck will carry the train to the desired point, such as a continuation of the main track.

45 In some cases it may be desired to shift a train or cars, say, from one track to another or off to a yard or siding. The tracks c run at an angle to or cross sections a and b . Trol-

leys or trucks, such as e , adapted to receive 50 the trucks d with trains, can be arranged for such shifting. The shifting-trucks when also made to move without smoke, steam, or fumes will avoid obscuring, which may be objectionable. The track-sections being on different 55 levels, the lowest section c can have its trucks e arranged to receive train-carrying trucks d , while the latter trucks on the level b can receive trains off the higher level a —that is, have their tops level, or practically so, with 60 the grade a .

The truck-tracks b and c can of course be applied at any required point or points along train-track a , since the invention is not confined to use in a tunnel, but can be used elsewhere, as may be called for.

65 The motive power of the trucks is independent of the motive power or locomotive of the train, and a third-rail or trolley arrangement can be suggested as a practical means 70 for moving the trucks.

In the drawings the shifting track-sections c are shown at right angle to the line $a b$; but of course the track-sections could be made to run in different directions, not necessarily 75 in those shown in the example.

The various trucks can be provided with electric or other danger-signals, either visual or audible, or both, to prevent a truck following another too closely or running into a truck 80 ahead, which may be stalled. Such signals can be of any suitable construction and applied as called for to indicate “danger” or “caution” or the distances between trains or trucks.

85 The truck can be made of suitable material, and an iron or fireproof truck or structure is considered advisable.

What I claim as new, and desire to secure by Letters Patent, is—

90 1. A railroad comprising a train-supporting section, a truck-supporting section on a level lower than the train-supporting section, a train-supporting truck on said latter section, and suitable means carried by said truck for propelling same.

95 2. A railroad comprising a train-supporting section, a section having a train-supporting

truck, and another truck-section for supporting or shifting the first-named truck and train.

3. A railroad comprising train-supporting sections and truck-sections, the latter made to run in different directions and being placed on different levels from one another and from the first-named sections, one of the sections having a truck for supporting a train, and

the other section having a truck for supporting the first-named truck with train.

In testimony whereof I have hereunto set my hand in the presence of two subscribing witnesses.

CHARLES W. HORNUNG.
